 Bendix Aviation Corporation, South Bend, Ind.,
 a corporation of Delaware

Application March 19, 1942, Serial No. 435,404

2 Claims. (Cl. 175—336)

This invention relates to electromagnetic apparatus, and particularly to the control of the action of an electromagnetically actuated rheostat.

In Patent No. 2,268,718, granted to Frederick Newton on January 6, 1942, there is disclosed a rheostat of the carbon pile type, in which the carbon pile is subjected to the difference between two forces of a magnitude large in relation to the pressure needed to vary the pile resistance over its useful range, these forces being derived from the pull of an electromagnet, the excitation of which is dependent on the regulating effect, and from an opposing spring.

As is well known, for constant excitation the pull of an electromagnet of usual design upon its armature depends on the length of the air gap between them and, subject to variation of the stray field and other disturbing factors, varies inversely as the square of the air gap length. In the Newton patent provision is made for a counter-balancing force which follows basically the same law of variation as the magnet pull, and the difference between these two forces of like characteristic is utilized as the regulating force.

This counter-balancing force is provided by a spring or beam which rests tangentially against an abutment attached to the electromagnet, with which abutment the spring is brought into surface contact over a continuously increasing length by movement of the armature towards the electromagnet. As the spring wraps upon the abutment, the length of spring subjected to further bending as the armature moves further toward the electromagnet continuously decreases. The spring thus shortens and becomes stiffer as the length of the air-gap lessens. Thus basic correspondence with the varying magnet pull results.

In the Newton patent, above identified, an attempt at temperature compensation is provided in the form of a spring abutment of bimetallic nature, in which the inclination of the abutment surface varies with temperature, the points of support of the spring moving in the direction of the spring pressure and therefore reducing that pressure as the temperature rises.

An object of the present invention is to substitute, for the temperature compensating means of the Newton patent, a temperature compensating construction of a novel character, acting to vary the air gap between the armature and fixed parts of the magnetic circuit, rather than to vary the inclination of the spring abutment.

This and other objects of the invention will become apparent from inspection of the following specification when read with reference to the accompanying drawing wherein is illustrated the preferred embodiment of the invention. It is to be expressly understood, however, that the drawing is for the purpose of illustration only, and is not designed as a definition of the limits of the invention, reference being had to the appended claims for this purpose.

In the drawing, reference characters 4, 5, 12, 13, 33, 34, and c designate parts corresponding to parts similarly designated in Fig. 11 of the Newton patent above identified. The bi-metallic coned disc 35, 36 of the Newton patent, on the other hand, has been eliminated, so that only the single metallic abutment piece 41 appears at the location occupied by such disc 35, 36 in the Newton patent. This abutment 41 fits within the extension 42 of the magnet casing 43, and rests against the annular magnetic ring 44, the latter being clamped at its periphery by the casing elements 42 and 43.

The carbon pile is made coaxial with the magnet casing 43 (as in the Newton patent) the carbon washers 12 being assembled upon a porcelain sleeve 13 encasing the armature spindle 5. At the outer end the pressure of the pile is taken by a stout carbon washer 33 carried by but insulated from crooked stanchions 34 fixed in a flange on the magnet body. The stanchions support the pile at a sufficient distance from the electromagnet for the winding of the latter not to be unduly affected by the relatively high temperature of the pile.

The spring 51 is (as in the Newton patent) a six-rayed plate spring clamped between the armature c and the upper washer 52 by any suitable means (such as the rivets indicated in Figs. 12 and 13 of the Newton patent) and having its rays engageable with the upper surface of abutment 41, so as to yieldably oppose the action of the magnetic field upon the armature c, as in the Newton patent.

Instead of varying the inclination of the surface of abutment 41, to compensate for temperature variations, I introduce a novel temperature variation responsive agency in the form of an auxiliary magnetic ring 56 and a bi-metallic washer 57, the former being supported by the latter in a position adjacent the main magnetic ring 44 (heretofore described) and being shiftable axially (to reduce the air gap between ring 56 and armature c) as the inner periphery of the bi-metallic washer 57 is caused to curl upwardly

by a rise in temperature due to the heat radiating from magnet winding 4. As the outer periphery of washer 57 is confined (although not mechanically clamped) against axial displacement, the major deflection will occur at the inner periphery, and such flexing will shift ring 56 to vary the air gap and thus compensate for temperature-induced variations in the strength of the magnetic pull.

The disclosed device may form part of the control circuit of an electric motor (as in Fletcher Patent No. 1,971,747) or of an electric generator, as in Fig. 7 of the Newton patent, above identified; or it may be used in other capacities where resistance variation is desirable.

What is claimed is:

1. In an electromagnet, an armature, a fixed core, a winding surrounding said fixed core, a pair of nested magnetic rings additional to, and distinct from, said armature and core, and inter-

posed between said winding and said armature, and heat responsive means in contact with said winding for moving one of said nested rings in relation to the other, to reduce the air gap between said rings and said armature.

2. In an electromagnet, an armature, a fixed core, a winding surrounding said fixed core, a pair of nested magnetic rings additional to, and distinct from, said armature and core, and interposed between said winding and said armature, and heat responsive means for moving one of said nested rings in relation to the other, to reduce the air gap between said rings and said armature, said heat responsive means comprising a bi-metallic washer interposed between said winding and said rings, said washer having heat absorbing contact with said winding along the major portion of its surface.
